UNITED STATES PATENT OFFICE.

JOHN A. GILMAN, OF SEATTLE, WASHINGTON.

CLAMP FOR CONCRETE FORMS.

Application filed December 1, 1927. Serial No. 237,023.

The invention relates to means for securing the members of concrete forms against separation while in use and is intended more particularly for application to forms for molding concrete or reinforced concrete columns. The object of the invention is to provide inexpensive and highly efficient devices whereby a cable or other flexible securing element may be securely tightened around the form so as to resist all tendency of the formed members to separate under the strain imposed thereon. Another object of the invention is to provide a device which will be firmly held to the form by the tension of the cable or other flexible element and which may be easily removed after the concrete has set, and another object of the invention is to provide a gripping and stretching device by which the cable or other flexible element may be readily gripped when it is to be placed under tension and released after it has been secured. These stated objects, and other objects which will incidentally appear in the course of the following description, are attained in such a device as is illustrated in the accompanying drawing, and the invention resides in certain novel features which will be particularly pointed out in the appended claims.

In the drawing:
30 Figure 1 is a top plan view of my improved clamp in operative position;

Fig. 2 is a side elevation of the clamp as it appears before the cable is connected therewith;

35 Fig. 3 is an end elevation of the clamp, and Fig. 4 is a side elevation of the cable gripper and stretching device with the cable in section so as to illustrate the position of the same relative to the gripper when the device is in use.

In the drawing, the reference numeral 1 indicates a portion of a concrete form which, in this instance, is polygonal and may, of course, be of any many-sided contour. The device of my invention includes a base plate 2 which has a flat face adapted to bear against a flat side of the form, as indicated in Fig. 1, and at one end is formed with a notch 3 to accommodate the anchoring end of the cable 4 or other flexible element 4. Upon the outer side of the base 2 adjacent the notched end thereof is a substantially triangular boss 5 having openings 6, 7 and 8 formed therethrough in triangular relation, the opening 6 being disposed on the central longitudinal

line of the base and communicating with the notch 3 through a channel, indicated at 9, in the inner or supporting side of the base, as will be understood. The openings 7 and 8 are disposed at opposite sides of the central longitudinal line of the base and in transverse alignment and are connected in the supporting side of the base by a channel, indicated at 10. The boss 5 terminates short of the notched end of the base whereby projecting ledges 11 are produced and a wall 12 is defined by the end of the boss at a right angle to the ledges 11 and transverse to the base. From the wall 12, a lug 13 projects in alignment with the notch 3, as clearly shown in Fig. 2. In attaching the cable to the base member, the end of the cable is inserted through the opening 6 from the inner to the outer side of the base so that the free portion of the cable will rest in the channel 9 and extend through the notch 3, as will be understood upon reference to Fig. 1. The end of the cable is then passed through the opening 7 across the base within the channel 10 and then outwardly through the opening 8 so that the extremity of the cable may pass through the bight formed at 14 and be firmly held to the base by drawing the bight tightly over the projecting extremity. This will be understood upon reference to Fig. 1, and it will be noted that the end of the cable is knotted or tied about the base so that it will be firmly held and cannot be accidentally detached therefrom. Extending from the boss 5 to the opposite end of the base plate 2 is a stationary jaw 15 which is preferably formed integral with the base and has a lateral portion 16 which constitutes a guide and support for the movable jaw 17, the two jaws being provided in their opposed faces with grooves 18 arranged to receive the free end of the cable 4, as shown in Fig. 1. In the illustrated embodiment of the invention, the grooves 18 are disposed at an angle to the base plate corresponding to the angular relation of the sides of the form, but it will be understood that the particular inclination or angular disposition of the grooves may be varied as circumstances may require or suggest. The jaws 15 and 17 have alined openings formed therethrough to receive a bolt 19 and the opening in the jaw 15 is internally threaded so that it may be engaged by the threads of the bolt and permit the bolt to move endwise through the jaw in adjusting the device. The

head of the bolt, shown at 20, bears against the outer side of the movable jaw 17 and the end of the bolt is upset or flanged, as indicated at 21, after the bolt has been fitted 5 through the jaws so that the movement of the bolt will be limited and complete separation with consequent loss of the parts will be prevented.

After the cable or other flexible binding 10 element has been passed around the form, its free end is engaged by a gripping and stretching member consisting of a jointed lever having a fulcrum member 22 and a handle member 23. These members of the lever are pivotally connected by a bolt or like device 24, the said pivot element being inserted transversely through an offset or perforated lug 25 formed on the fulcrum member 22 and a perforated ear 26 formed on the end of the 15 handle member and fitting within a notch 27 formed in the lug 25, as shown clearly in Fig. 4, the ear 26 being offset from the handle member so that, if the handle member be rocked about the pivot 24 in one direction, it will 20 release the cable, as indicated by the dotted lines in Fig. 1, whereas, if it be rocked in the opposite direction, it will grip the cable, as shown in full lines in Fig. 1. The handle member 23 is formed with a lateral 25 gripping shoulder 28, preferably provided with a notch 29 to fit around and grip the cable, while the fulcrum member is provided with a corresponding groove or recess 30 for a like purpose, as will be understood upon 30 reference to Fig. 4, it being noted upon reference to Fig. 1 that the opposed surfaces of the handle and fulcrum members provide straight jaws or gripping surfaces to engage the opposite sides of the cable so that the free 35 end thereof will be firmly held by and between the two members of the lever when the latter is being manipulated to put the cable under tension. Upon the free end of the pivot bolt 24 is mounted a nut 31 and a washer 40 32, and between the washer and the fulcrum member of the lever a spacer sleeve or collar 33 is fitted upon the bolt, so that the nut may be turned home to firmly retain the pivot bolt in its position in the lever but at the same 45 time space will be provided to accommodate the coils 34 of a spring which has its ends 50 35 attached to the handle and fulcrum members respectively of the lever. The spring tends constantly to hold the gripping elements 55 closed upon the cable. At the free end of the fulcrum member, there is a notch 36 whereby the fulcrum member may span the lug 13 and the portion of the cable which passes through the notch 3 of the base, and 60 the ends of the fulcrum member at the sides of said notch are formed into arcuate knobs or rockers 37 which are adapted to rest upon the ledges 11 and against the shoulder 12, as shown in Fig. 1, while the lever is being 65 rocked to stretch the cable. The lug 13 acts as

a retainer to prevent the lever slipping transversely of the base while being rocked. It will now be understood that the jaws 15 and 70 17 of the clamp are separated so that the cable, after being passed around the form, may be passed between the jaws in position to fit within and be engaged by the grooves 18 after it has been drawn taut. The base 2, of course, is placed flat against the side of the form and the lever is rested against the ledges 11 and the shoulder 12 in the position shown in Fig. 1 so that the free end of the cable may be placed between the opposed surfaces of the fulcrum and handle members thereof, the handle member being swung forward to the 80 position shown in dotted lines to separate the gripping surfaces. If the handle be then released, the spring will close the opposed surfaces 25 and 28 upon the cable with sufficient force to maintain the engagement. The lever is then swung rearwardly and the cable will be firmly gripped in the notches 29 and 30 and placed under tension, and the operator may maintain his hold upon the lever until the jaw 17 can be moved into binding engagement with the cable by rotation of the bolt 19. If the lever be swung forward under light force, the grippers will slide along the cable, without being released, to a new gripping position, and the operator may thus obtain what may be described as a toothless ratchet action. It will be noted that the bolt 19 when rotated will move endwise through the jaw 15 and as the head of the bolt is in contact with the side of the jaw 17 the rotation of the bolt in one direction will cause the latter jaw to move toward the jaw 15 and thereby firmly clamp the cable between the two jaws. The lever may then be withdrawn and operated in connection with a second clamp so as to secure a second cable about the form and the cables will be held by the clamps until released by applying a reverse movement to the several bolts 19. The tension of the cables will hold the several bases 2 firmly against the concrete forms without requiring the clamps to be nailed or otherwise positively fastened to the form and, therefore, there will be no difficulty experienced in withdrawing the clamps and the cables after the concrete has set. The device is exceedingly simple in construction and is highly efficient in operation.

It will be understood that in commercial practice, the device may be arranged to suit the convenience of right or left-handed operators and that various changes may be made in the form, proportions or minor details, the drawings being illustrative only.

Having thus described the invention, I claim:

1. Means for the purpose set forth comprising a base member constructed at one end with openings therethrough in substantially triangular relation to receive an anchoring

end of a flexible securing element, and means mounted on the opposite end of the base to secure the free end of the flexible element.

2. Means for the purpose set forth comprising a base member constructed at one end with a longitudinally extending channel and having openings formed therethrough in substantially triangular relation, jaws mounted upon the opposite end of the base member, and means for effecting relative movement of the jaws whereby they may be caused to clamp the free end of a flexible element, the opposite end of said element being disposed within the channel and threaded through said openings whereby to be anchored to the base member.

3. Means for the purpose set forth comprising a base plate, means at one end of the base plate whereby an end of a flexible element may be anchored, a jaw fixed to the opposite end of the base plate, a movable jaw arranged to cooperate with the fixed jaw whereby the free end of the flexible element may be engaged and secured; and a bolt 25 threaded through the fixed jaw and passing loosely through the movable jaw and having its head bearing against the outer side of the movable jaw and its end provided with a stop member beyond the outer side of the fixed 30 jaw.

4. Means for the purpose set forth comprising a base plate constructed at one end to anchor an end of a flexible element, clamping jaws mounted at the opposite end of the base 35 plate to receive and secure the free end of the flexible element, a ledge at the first-mentioned end of the base plate, a shoulder projecting from said ledge, and a lever constructed to grip the free end of the flexible 40 element and adapted to rest against said ledge and bear against said shoulder whereby to rock thereon to tension the flexible element.

5. Means for the purpose set forth comprising a base plate, a rest at one end of the 45 base plate, a lug projecting longitudinally from said rest, jaws at the opposite end of the base plate adapted to engage and secure the free end of a flexible element which has its opposite end anchored to the base plate at the 50 rest thereon, and a lever provided at one end with a notch to span said lug, and rockers to fulcrum upon the rest on the base plate, the lever being constructed between its ends to grip the free end of the flexible element 55 beyond the jaws.

6. Means for the purpose set forth comprising a base plate, jaws at one end of the base plate to secure the end of a flexible element which is anchored to the opposite end of

the base plate, a gripping lever comprising 60 a handle member, and a fulcrum member each having an offset and provided adjacent the offset with jaws adapted to engage the flexible element beyond the jaws on the base plate, a pivot member inserted through the 65 offsets of the lever members, and a spring coiled around the pivot member and having its ends attached to the members of the lever.

7. Means for the purpose set forth comprising means for anchoring one end of a cable, means for securing the free end of the cable after it has been put under tension, and a tensioning device consisting of pivotally connected members having opposed gripping surfaces and means for yieldably holding the 75 gripping surfaces in engagement with the cable.

8. Means for the purpose set forth comprising a base, means at one end of the base to anchor a flexible element, and devices at 80 the opposite end of the base movable in rectilinear paths diametric to the flexible element whereby to clamp the flexible element without sliding thereon.

9. Means for the purpose set forth comprising a base, means at one end of the base to anchor a flexible element, devices at the 85 opposite end of the base movable in rectilinear paths diametric to the flexible element whereby to clamp said element without sliding thereon, and means operable on the base 90 for applying tension to the flexible element.

10. In a device for the purpose set forth, a tensioning lever consisting of a handle member, and a fulcrum member provided with offsets at their meeting ends, a pivot inserted 95 through the offsets, and lateral gripping shoulders on said members.

11. In a device for the purpose set forth, a tensioning lever consisting of a handle member, and a fulcrum member provided with offsets at their meeting ends, a pivot inserted 100 through the offsets, lateral gripping shoulders on said members adjacent the offsets, and means engaged with said members for 105 yieldably holding the gripping shoulders in engagement with an element to be tensioned.

12. In means for the purpose set forth, a tensioning lever comprising a handle member, and a fulcrum member each having an 110 offset and provided adjacent the offset with jaws adapted to engage a flexible element, a pivot member inserted through the offsets, and a spring coiled around the pivot member 115 and having its ends attached to the members of the lever.

In testimony whereof I affix my signature.
JOHN A. GILMAN. [L. s.]
